UNITED STATES PATENT OFFICE.

PAUL J. WEDER, OF CHICAGO, ILLINOIS, ASSIGNOR TO SHARP & SMITH, OF CHICAGO, ILLINOIS, A FIRM.

VETERINARY SURGEON'S FLOAT.

SPECIFICATION forming part of Letters Patent No. 703,867, dated July 1, 1902.

Application filed December 28, 1901. Serial No. 87,550. (No model.)

To all whom it may concern:

Be it known that I, PAUL J. WEDER, a citizen of the United States, residing at Chicago, in the county of Cook and State of Illinois, have invented certain new and useful Improvements in Veterinary Surgeons' Floats, of which the following is a specification, reference being had to the accompanying drawings.

10 This invention relates to improvements in veterinary surgeons' instruments for filing down the teeth of horses, such style of instrument being technically known as a "float." Instruments of this character comprise a rasp, 15 a holder therefor, and a handle affixed to the holder. The holder in general use consists of a heavy flat plate having raised sides in which are formed grooves adapted to receive the side edges of the rasp and of course leaving 20 one face of the rasp exposed. The forward end of such holders in general use is provided with an upturned piece, against which the forward end of the rasp abuts and at its rear end is held in place by a shoulder formed on the handle-bar, which is forced up against said rear 25 end as the handle-bar is screwed into place. In another form of device employing substantially the same holder a loose piece on the screw-threaded portion of the handle-bar is 30 employed to bear against the rear end of the rasp. In both these forms of construction it is evident that the rasp must be withdrawn from the rear end of the holder only, owing to the fixed stop at the forward end of such holder, 35 and it is evident also that the rasp must substantially conform in length to the length of the holder. Both forms are open to objections also in that in the first-described construction the handle-bar must be wholly dis- 40 connected from the holder in order that the rasp may be removed, and in the second-described construction the loose rasp-retaining piece referred to while turning sufficiently to allow of the removal of the rasp upon a 45 mere loosening of the connection between the handle-bar and holder is apt to become lost or mislaid when such handle-bar is entirely disconnected from the holder, which disconnection has frequently to be made to enable 50 the handle-bar to be secured to another holder, it being understood that one handle

usually suffices for two or more holders that are adapted to be used at different angles. Furthermore, a separate loose retaining-piece has to be provided for use with each of the said two or more rasp-holders, as the retaining-piece that will properly hold the rasp in place when the handle-bar is attached at an angle to the rasp-holder will not answer when such handle-bar is straight or in line with the said holder, and vice versa. This provision of extra retaining-pieces adds, of course, to the expense and also increases the liability of the instrument being rendered useless through the loss of such small pieces. 55

It is the object of my invention to obviate the objections above specified and to provide an instrument for the purpose stated that will securely hold or bind the rasp within its holder, that will permit the rasp to be released from its binding engagement with its holder by a slight movement of the handle-bar, that will permit of an equally firm holding or binding of the rasp within its holder whether such holder be of the construction 70 that allows the handle-bar to be secured at an angle to it or one in which such handle-bar is secured to and in a straight line with the holder, and this without the use of any extra or different part or parts for engaging the 75 rasp, and that will permit of the use of a rasp of greater or less length than its holder. These objects I accomplish by the devices and combinations of devices illustrated in the drawings and hereinafter specifically de- 80 scribed.

That which I regard as new will be set forth in the claims.

In the accompanying drawings, Figure 1 is a side elevation. Fig. 2 is a plan view. Fig. 90 3 is a longitudinal section at line 3 3 through the rasp-holder and rasp, a portion only of the handle bar or rod being shown. Fig. 4 is a cross-section at line 4 4 of Fig. 1; and Fig. 5 is a view similar to Fig. 3, except that 95 the holder is adapted to have the handle bar or rod attached to it at an angle.

Referring to the several figures of the drawings, in which corresponding parts are indicated by the same reference characters, 6 in- 100 dicates the rasp-holder, consisting of a flat plate, upon opposite sides of which are formed

two vertical flanges 7, cut away on their inner faces to form grooves, as best shown in Fig. 4, into which grooves project the side edges of the rasp to be employed, such rasp 5 being indicated by 8. The grooves are unobstructed at both ends, and the rasp can therefore be inserted or withdrawn at either end of the holder, and a rasp of greater length than the length of the holder can be employed, if desired, whereas in the floats in general use the rasp must be approximately of the same length as the holder and can only be inserted or withdrawn from the rear end of the holder, as hereinbefore explained.

15 9 indicates a thickened portion on the under face of the plate, in which is formed a screw-threaded opening 10, adapted to receive a screw-threaded shank 11 on the forward end of a handle bar or rod 12.

20 13 indicates a lug formed with or rigidly secured to the bar or rod 12 immediately in rear of the screw-threaded shank 12 and adapted when the said shank 12 is screwed nearly to its limit in the hole 10 to come in contact 25 with the under surface of the rear end of the rasp 8, which rear end, as shown, is caused to project slightly beyond the end of the holder. The effect of the contact of the lug 13 is to force the rasp up tightly against the 30 upper edges of the grooves in the vertical flanges 7, where it will be held immovable until the pressure is released by a reverse turn of the bar or rod 12. Inasmuch as both sides of the rasp are usually cross-milled or 35 roughened it will be evident that the engagement between the parts when locked in the manner described will be an exceedingly strong one, so that there is no chance of the rasp slipping in the slightest degree when in 40 use. The part 13 is shown as a disk secured eccentrically to the bar or rod 12, thus giving to it a cam action with respect to its engagement with the rasp, and this is the form that I prefer, as it is evident that if by wear 45 one portion of the face becomes worn a new engaging portion of the face can be turned to contact with the face of the rasp. Other shapes could of course be given to this part and accomplish the same result.

50 50 In Fig. 5 I have shown the invention in connection with a holder having the handle bar or rod attached at an angle. The rear end of the holder is formed at an obtuse angle to the body portion instead of at right angles, 55 as in the construction shown in the other figures of the drawings; but the operation of the several parts is exactly as before described. In this construction, however, the edge of the lug carried by the bar or rod contacts 60 the rasp instead of the contact being by the full width of its edge, as shown in the other figures. The several parts in the con-

struction shown in Fig. 5 differing but slightly from the construction and arrangement shown in the other figures, I have indicated 65 the several parts in Fig. 5 with the same reference-numerals as in the other figures, but with the addition of the letter "a" to each reference-numeral.

By my invention a cheap, simple, and very 70 effective device is produced possessing all the advantages of the devices for the same purpose that are now on the market and obviating the disadvantages hereinbefore pointed out as appertaining to such other constructions.

That which I claim as my invention, and desire to secure by Letters Patent, is—

1. The combination with a rasp-holder, and a rasp mounted thereon, of means for engaging the upper surface of the rasp, a handle bar or rod rotatably secured to one end of said holder, and a device integral with said bar or rod and adapted upon the rotation thereof to contact the under face of the rasp and force 85 it upward into binding engagement with the said means for engaging the upper surface of the rasp, substantially as specified.

2. The combination with a rasp-holder consisting of a plate provided with grooved side 90 flanges, and a rasp slidably mounted thereon, of a handle bar or rod rotatably secured to one end of said holder and provided with an integral lug adapted to be forced against the under face of the rasp, substantially as specified. 95

3. The combination with a rasp-holder consisting of a plate provided with grooved side flanges, and a rasp slidably mounted thereon, of a handle bar or rod rotatably secured to 100 one end of said holder and provided with an integral lug having a cam-face, said rod or bar being adapted to be moved to force said cam-face against the under face of the rasp, substantially as specified. 105

4. The combination with a rasp-holder consisting of a plate provided with grooved side flanges, and a rasp mounted thereon with its edges within the grooves in said flanges and its rear edge projecting beyond the rear end 110 of the holder, said grooves being unobstructed at each end, of a handle bar or rod rotatably secured to the rear end of said holder, and a lug carried by said handle bar or rod and adapted upon the rotation of said bar or rod 115 to contact the under surface of the projecting lower end of the rasp and force said rasp up into binding engagement with the upper faces of the grooves in the side flanges, substantially as specified.

PAUL J. WEDER.
